UNITED STATES PATENT OFFICE.

CHARLES G. SMITH, OF CAMBRIDGE, MASSACHUSETTS, ASSIGNOR TO CHARLES F. MACGILL, OF CAMBRIDGE, MASSACHUSETTS.

SPEEDOMETER.

1,384,809.

Specification of Letters Patent. Patented July 19, 1921.

Application filed August 22, 1919. Serial No. 319,289.

To all whom it may concern:

Be it known that I, CHARLES G. SMITH, a citizen of the United States, residing at Cambridge, in the county of Middlesex and 5 State of Massachusetts, have invented certain new and useful Improvements in Speedometers; and I do hereby declare the following to be a full, clear, and exact description of the invention, such as will enable others 10 skilled in the art to which it appertains to make and use the same.

The present invention relates to speedometers and more particularly to speedometers of the type in which a torque is set up 15 through the rotation of a member within a viscous liquid.

Patent No. 1,271,092, granted to Charles G. Smith, illustrates a speedometer of this general type in which the inner rotating 20 member is connected to the usual drive shaft through a magnetic clutch which permits of hermetically sealing the containing member in which the viscous fluid is received with all of the advantages attendant thereon.

5 The object of the present invention is to provide certain further improvements in speedometers of this general type by which the construction is simplified and the accuracy of speed indication is increased. To 30 this end one feature of the invention contemplates the provision of a fluid containing member connected directly to the usual drive shaft to rotate therewith, an inner member received within the fluid containing member 35 and adapted to be rotated thereby through the viscosity of the liquid in the containing member, and an outer indicating member normally restrained against rotary movement and having a magnet which clutches 40 the outer member to the inner member so that the torque exerted upon the inner member is transmitted directly to the indicating member.

With this construction the magnet and inner member do not rotate with the drive shaft but are normally stationary at any given speed of rotation, the position of the members depending upon the speed at any given time. This construction, in addition to 50 its simplicity, has the advantage that the indicating cup and magnet may be made light in weight to respond instantly to variations in position of the inner member, yet

vibrations or rapid fluctuations in the speed of the drive shaft are not transmitted to the indicating member. This is due partly to 55 the fact that the inertia of the inner member tends to maintain it in the same position and partly to the design of the instrument by which a relatively thick copper screen is 60 interposed between the magnet and the inner member so that any movement in the magnet immediately produces eddy currents in the copper screen which react to prevent such a 65 movement. Due to these factors the indication afforded by the present instrument is remarkably steady and free from fluctuations of the indicating dial.

The drawing illustrates a partially diagrammatic view of an instrument embodying the several features of the invention.

In the illustrated embodiment of the invention shown in the drawing the usual drive shaft is indicated at 10. This shaft is provided at the upper portion with a head 12 70 reduced in diameter at its upper portion, as indicated at 13, and co-operating with a shell 14 to provide a closed fluid containing member. The shell 14 is conveniently made as a steel stamping in the form of a cup with 75 the lower edge rolled into a peripheral groove 16 formed adjacent the base of the head, as shown in the drawing. This construction provides an inverted cup-shaped space in which the liquid is contained. The 80 head 10 is also provided with an axial recess 17 communicating with the liquid space at the top and with a branch passage 18 which connects the recess 17 and the bottom of the 85 annular liquid space to prevent any possibility of the formation of air pockets. An 90 inner rotary member 20 in the form of an inverted cup is received within the space formed by the head 12 and shell 14 and is mounted for rotation upon a spindle 21 95 which is positioned in alignment with the axis of rotation of the drive shaft and head 12 and has its upper and lower ends journaled in bearings 23 and 24 formed, respectively, in the shell 14 and the bottom of the 100 recess 17. The inner member is formed of soft iron or other magnetic material and may be constructed by interposing between two cups of thin non-magnetic material a thin strip of iron bent into cylindrical form. 105 This provides a construction having a

smooth unbroken exterior to eliminate all force other than the desired drag of the liquid and at the same time provides the necessary magnetic material by which the 5 inner member may be magnetically clutched to the permanent magnet.

It is found that a liquid which may be usually employed to exert the desired torque upon the inner member is mercury with a 10 slight percentage of impurities therein, possibly not over one per cent. of copper, zinc, or other material. The impurity makes it wet certain solid surfaces better than pure mercury. This liquid is practically unaffected by temperature and owing to its character exerts a relatively large torque upon the inner member at the different speeds of the drive shaft.

The indicating member comprises an inverted cup 25 of celluloid or other material 20 having a permanent steel magnet 26 connected rigidly therewith. The magnet, as shown in the drawings, extends downwardly from its connection with the indicating cup 25 in close proximity to the shell 14. Both the magnet and indicating cup are mounted for rotation coaxially with the head 12 and inner member and to this end a supporting spindle 27 is journaled at its upper and 30 lower ends, respectively, in bearings 28 and 29 mounted in alignment with the bearings for the inner member. The lower bearing 29 is supported in a copper cup 30 which is secured rigidly to the frame of the instrument in any suitable manner not shown. This cup is relatively thick and heavy and in addition to providing a rigid bearing for the magnet and indicating members serves to 35 dampen the movements of the magnet and indicating member due to eddy currents which are set up in the relatively thick sheet 40 of copper. A spiral spring 32, connected to the spindle 27, normally tends to maintain the magnet and indicating member in a zero 45 position and to restrain the indicating member against movement with the inner member 20.

In the operation of the instrument the fluid containing member consisting of the 50 head 12 and the shell 14 is rotated with the drive shaft, exerting a torque upon the inner member 20 through the mercury or other liquid contained therein. This drag exerted upon the inner member tends to rotate the latter with the drive shaft. The inner member, however, is restrained against such movement by being magnetically clutched to the indicating member 25, so that in operation the inner member 20 and the indicating member 25 move to a position determined by the speed of the drive shaft and remain stationary in this position so long as the speed remains unchanged. Owing to the inertia of the member 20 and the eddy 60 currents set up in the copper shield 30, vi-

brations and sudden fluctuations of speed in the drive shaft are not transmitted to the indicating member. This construction provides an exceedingly simple and efficient mechanism for indicating at all times the 70 speed of the drive shaft.

While it is preferred to employ the specific construction and arrangement of parts shown and described, it will be understood that this construction and arrangement is 75 not essential except so far as specified in the claims, and may be changed or modified without departing from the broader features of the invention.

The invention having been described, what 80 is claimed is:

1. A speedometer comprising a drive shaft, a rotary fluid containing member connected thereto, an inner member of magnetic material journaled coaxially within the fluid containing member, an indicating cup journaled for rotary movement coaxially with the inner member, and a magnet associated with the indicating member to clutch the indicating member to the inner member. 90

2. A speedometer comprising a rotary fluid containing head, a cup received within the head and journaled for rotation coaxially with the head, an indicating member, means for normally restraining the indicating member against rotary movement, and a magnet connected to the indicating member and adapted to clutch the indicating member to the inner rotary member. 95

3. A speedometer comprising a rotary 100 head having a fluid chamber in the form of an inverted cup with an axial fluid passage communicating with the chamber, a cup-shaped member received within the fluid chamber for rotary movement about the axis 105 of rotation of the head, an indicating member journaled for rotation about the same axis, and a magnet connecting the inner cup-shaped member and indicating member to cause the two members to move synchronously. 110

4. A speedometer comprising a sealed fluid containing head rotating with the drive shaft, an inner member loosely journaled for rotary movement about the axis of rotation of the head and composed of magnetic material, an indicating member journaled above the head for rotary movement about the same axis, a magnet connected to the indicating member, and a copper screen 120 interposed between the magnet and the inner member. 115

5. A speedometer comprising a rotary fluid containing head having a reduced upper portion, a metal shell in the form of an 125 inverted cup received over the head and having its lower edge pressed into an annular groove formed in the head to provide a sealed fluid containing chamber, a liquid contained within the chamber, an inner 130

member received within the chamber and loosely journaled for rotation about the axis of rotation of the head, and an indicating member magnetically clutched to move with the inner member.

6. A speedometer comprising a rotary head having a fluid chamber, liquid mercury

received within the chamber, a member received within the chamber adapted for rotation about the same axis as the head, and an indicating member journaled for rotation about the same axis and magnetically clutched to the inner member.

CHARLES G. SMITH.
